UNITED STATES PATENT OFFICE

CARLOS KREBS, OF BOSTON, MASSACHUSETTS

REPRODUCING MECHANISM

Application filed March 14, 1929, Serial No. 347,065, and in Germany January 25, 1929.

This invention relates to an improvement in reproducing mechanism of the type shown in my copending application Serial No. 288,023, filed June 25, 1928, and which may be 5 employed in various machines, as for example in the torch cutting machine disclosed in that application, and which includes means for controlling the reproductive movements of one or more tools or other elements used 10 in cutting, welding, profiling and other machinery having drives which are either directly or indirectly controlled.

The use of cutting machines of this character has increased greatly within the past 15 few years for the purpose of producing standard parts which must be replaced periodically, such as locomotive parts, or for producing in large quantity parts to be used for the construction of new machinery. The 20 template with which the tracer coacts is supposed to serve as a long-lasting pattern by the use of which parts are reproduced correctly so long as the pattern is serviceable, thus making it possible to produce large 25 quantities of duplicate parts which are to be used in constructing a large number of machines or for replacing parts of previously manufactured machines which became broken or impaired in any way.

30 For example, it is the usual custom in railroad shops at the present time to produce about two hundred standard parts and keep them always in stock. These parts are made from templates from which hundreds of 35 parts are made a year. It is, of course, essential that the reproductions be always the same, and it is accordingly necessary that the specific features of the cutting machines must be such that the parts are reproduced 40 correctly and permanently. Moreover, it is now the practice in electrical companies to produce smaller motors and generators in mass production, using steel elements instead of castings. One factory of this type now turns 45 out 800 motor frames per week, each motor being provided with four legs, and those legs must be so formed that they can be fitted to the frames without further machining, and hence it is necessary that the cutting 50 machines reproduce permanently correct parts

without requiring close attention by the operator.

In order that a cutting machine be formed to operate in the accurate manner above mentioned, three essential features must be provided: First, the tracer and cutting torch must be mounted upon a suspension system and be freely movable thereover in any or all directions in a horizontal plane; second, the tracer and torch must be so mounted upon 55 the suspension system that they, at all times, work in a vertical plane; third, the mechanism by which the movement is transmitted from the tracer to the torch must compel the torch to follow exactly the path prescribed 60 by the tracer.

Obviously all these points are fundamentally interdependent and if in any of these features the machine is not properly designed, accurate reproduction can not be relied upon. The suspension system for the tracer and the torch must be of a kind that can not possibly get out of the exact horizontal plane and must be of substantial and rigid construction permanently unaffected 70 by any moving weights or strains. If the suspension system does not remain in the horizontal plane at all times, it obviously follows that the tracer and torch mounted thereon can not always work in the vertical 75 position, and if the tracer and torch are not so constructed as to work in a vertical plane, then, even if the suspension system therefor were perfectly designed, the result of the operation of the machine will be unreliable. In 80 other words, both the support and the tracer and torches must be so designed that they keep within their respective planes permanently without any possibility of being shifted therefrom, either by reason of any faulty 85 construction, or by reason of the changing of the weights and strains which take place 90 during the operation of the machine.

In order that the relative movement be properly transmitted between the tracer and the torch, the means for so doing must be sensitive, engaging instantly and forcibly without the possibility of ever developing any lost motion. Obviously this transmission means can not be a part of the supporting 95 100

mechanism because the continuous shifting of the strains would destroy its value. In other words, the transmission means must transmit movement and can not be used for any other purpose.

Many designs of cutting machines have been developed, but it has been found that they do not comply with the three requirements above given. If the suspension system for the mechanism is supported at one end only, it necessarily must follow that the continual shifting of the weights during the operation of the machine will have a tendency to move the suspension system out of the exact horizontal plane which it occupied when the machine was new. Another objection to these machines is the fact that in many cases the transmission means acts wholly or in part as a support for the tracer and torch.

The machine which is here shown, for the purpose of illustration, embodies a torch cutting machine in which the movement of a plurality of torches is controlled by and each torch reproduces the movement of a tracer which is guided by a suitably formed pattern or template has been developed for the purpose of complying with each of the three requirements. Thus, the suspension system is supported at its center and the tracer and torch mechanisms are so arranged relative to this center support that they at all times balance each other and no undue strain is applied to the support at any time during the operation of the machine. Furthermore, the tracer and torches are freely movable vertically and in exact parallelism, and finally, the transmission means functions solely for that purpose and has no load supporting function at any time. Therefore, the torches will cut from the material upon which they work a plurality of articles which correspond in every particular to the pattern or template.

The primary object of this invention is to provide a reproducing mechanism so constructed that a plurality of articles may be simultaneously made by the operation of tools actuated by a single pattern or template controlled element.

Another object of this invention is to provide a reproducing mechanism embodying a tracer wheel guided by a template upon which it rests, and means carried by the tracer wheel support for engaging the template to insure the movement of the wheel at all times in conformance with the contour thereof.

A further object of this invention is to provide in a reproducing mechanism transmission means which operate in a horizontal plane to transmit motion from the tracer mechanism to the torch mechanism.

Other objects of this invention reside in the details of construction hereinafter set forth as will be apparent to one skilled in the

art from a consideration of the following specification taken in connection with the drawings which form a part thereof, and in which:

Fig. 1 is an elevation of a reproducing mechanism embodying this invention;

Fig. 2 is a plan view thereof illustrating primarily the suspension and transmission means;

Fig. 3 is a sectional view on a larger scale of the tracer;

Fig. 4 is a side elevation on a similar scale of the lower portion of the tracer; and

Figs. 5 and 6 are sectional detail views illustrating portions of the transmission means.

The embodiment set forth in the drawings and described in detail in the specification was selected as illustrative and not as limitative, it being understood that other embodiments can be made in which the subject matter of this invention may be incorporated.

Referring particularly to Figs. 1 and 2 of the drawings, it will be noted that the reproducing mechanism includes a suspension system here shown as comprising a pair of platforms 10, each of which is provided with a centrally located pedestal 11 by which the platform is rotatably supported in a horizontal plane. Suitably formed pairs of carriages 12 and 13 respectively support the tracer and torch mechanism, the movement of either pair being transmitted to the other by means of a transmission system 14. The pairs of carriages 12 and 13 are mounted upon the platform 10 and their entire weight is carried thereby, the transmission system 14 having no weight supporting function whatever. The suspension system, as will be disclosed below, thus insures that the movement of the carriages shall be at all times in a horizontal plane. The carriages 12 are joined by a cross beam 15 suitably secured to posts 16 in the carriages, and the carriages 13 are similarly joined by a cross bar 17 carried by posts 18 in the carriages. Thus each pair of carriages moves as a unit.

Each pedestal 11 comprises a fixed central column 20 mounted on a base 21 and provided with a capital 22 upon which the platform 10 rests. The base 21 may support both pedestals and be mounted upon parallel tracks 23 suitably supported upon a standard 24, or there may be separate bases 21 suitably joined to move as a unit over the tracks 23. In the base 21 are mounted one or more axles 25 provided with wheels 26 which engage the tracks 23. One pedestal 11 also may be provided with a motor 27, a suitably formed gear box 28, a shaft 29, and a worm and gear assembly 30, whereby one of the shafts 25 is rotated. The operation of the motor by this construction causes the base 21 and the pedestals 11 and all the parts

carried thereby to reciprocate over the track 23. Each capital 22 secured to its platform 10 is mounted upon the column 20 by anti-friction means (not shown) so that it can 5 rotate freely thereon about the vertical axis 31, thus permitting it, together with its platform 10 and the associated parts, to rotate about such axis as a center. At one side of the base 21 is provided a table 35 which 10 supports the template 36 by which the tracer mechanism is controlled. At the other side of the base 21 is provided a table 40 on which is supported the work 41 to be engaged by the torch mechanism.

15 Each platform 10 is provided with a pair of parallel tracks 45 over which the tracer carriage 12 and the torch carriage 13 travel. Each of the carriages 12 and 13 comprises a frame 46 which is supported by a plurality 20 of rollers 47, which rollers rest upon and are guided by the tracks 45.

The tracer mechanism includes a tracer 50 supported upon the cross beam 15 which is connected to the carriages 12 in such a 25 manner that the latter are free to oscillate relative to the ends of the beam. This may be attained in any desired manner, as for example, securing the posts by suitable ball and thrust bearings to the ends of the beam, so that the beam can turn easily thereon when 30 required during the operation of the machine. In the center of the beam 15, preferably midway between its ends, is an aperture 51 through which passes a sleeve 52 depending 35 from a plate or disk 53 supported upon the beam 15 as by legs 54, and secured thereto in any suitable manner.

The tracer 50 is particularly shown in Figs. 3 and 4 of the drawings on a large scale. 40 Supported upon the plate or disk 53 by anti-friction bearings 55 is a turntable 56 which carries a motor 57 by means of uprights 58. Rotatably mounted in bosses 60 formed on the uprights 58 is a shaft 61 which is actuated 45 through a worm and gear assembly 62 by the motor 57. Mounted to rotate upon the turntable 56 between the uprights 58 are gear wheels 63 which are driven from the shaft 61 by intermeshing bevel gears 64. The 50 turntable 56 has a central opening 65 within which a floating guide 66 preferably in the form of a tube extends. Mounted at the lower end of the tube 66 is a block 67 provided at its lower end with arms 68 which 55 support a wheel shaft 69. Mounted upon the shaft 69 between the arms 68 is a wheel 70 which is driven by the motor 57 through the gears 63. The gears 63 mesh with spur gears 71 mounted upon the upper ends of shafts 60 72 which extend through the tube 66 and block 67 terminating between the arms 68. The lower ends of the shafts 72 are provided with beveled gears 74 which mesh with gear teeth 75 formed on the wheel 70. The wheel 65 70 is thus positively driven from the motor

57 by gearing which engages both sides of the wheel, thus equalizing the pressure thereon and preventing the application of any undue strain against one side thereof.

The template 36 comprises a metal strip 76 70 which is bent in any suitable form and riveted to a supporting plate. The wheel 70 includes a central annular flange 77 which rests upon the upper face of the strip 76. In order to hold the wheel in this position upon the strip, there are provided rollers 80 which rest against the sides of the strip. These rollers are vertically supported in levers 81 pivoted upon rods 82 carried by the arms 68. One or both of the levers 81 may be provided with an extension 83 which engages bracket 84 carried by the block 67. The bracket 84 is provided with a plurality of holes 85 and the extension 83 is provided with a single hole so that a pin 86 passing through one 80 of the holes 85 in the bracket 84 and through the hole in the extension 83 holds the rollers 80 in any desired position. The preferred position is that shown in Fig. 4 in which the rollers 80 are slightly in advance 90 of the contacting portion of the wheel 70. It has been found when so arranged that the wheel 70 will follow the path defined by the strip 76 without difficulty. The conformation of the upper end of the floating tube 66 95 and of the opening 65 is such that while the tube and its parts are free to reciprocate relative to the turntable 56, any rotation of the tube around its vertical axis 90 will cause the turntable 56 to rotate similarly.

The torch mechanism comprises a plurality of torches 100 supported at the desired points upon the cross bar 17. The bar 17 is carried by the posts 18 through suitable ball and thrust bearings and may be extended to the length desired beyond the platforms 10. Each torch 100 may comprise a tube 101 which extends through a collar 102 clamped by arms 103 upon the bar 17. Suitable means (not shown) may be provided to raise or lower the torch 100 as required and the gas or other fuel by which the flame of the torch is produced passes through the tube 101 to the outlet at its lower end in the usual manner.

115 As is clearly shown in Fig. 2 of the drawings, each platform 10 supports a tracer carriage 12 and a torch carriage 13 which carriages are connected by transmission means 105 so that any movement of the carriage 12 over the platform 10 causes a movement of the carriage 13 over the platform 10 to the same extent but in the reverse direction. The transmission means 105 is similar in many respects to that shown in my copending application, but differs therefrom in certain details of construction as will be pointed out below, and in the fact that the various elements operate in a horizontal plane rather than in a vertical plane.

The means 105 comprise a pair of rack bars 106 and a gear 107 with which the teeth on the bars mesh. The gear 107 is mounted upon a vertical stub shaft 108 carried by the platform 10 over the pedestal 11, preferably in the vertical axis 31. Suitably mounted idler rolls 109 (see Fig. 6) hold the teeth of the bars 106 in mesh with the gear 107. The outer ends of the bars 106 may be attached to the carriages 12 and 13 by the means shown in Fig. 5. Mounted upon the frame 46 of the carriage is a Z-shaped bracket 110 which is adjustably secured to the frame by set screws 111 passed through slots 112. The bracket 110 terminates in an outwardly projecting tongue 113 and projecting from the bracket above and parallel to the tongue 113 is a second tongue 114. The end of the bar 106 enters the space between the tongues and is fixed therein by set screws 115 carried by the tongues. The tips of the screws enter depressions 116 in the upper and lower faces of the bar and thus permit the bar to oscillate slightly, should such movement be necessary at any time, without impairing in any respect the operation of the transmission means.

The construction of the reproducing mechanism thus described is such that the movement of the tracer wheel 70 over the strip 76 caused by the motor 57 is transmitted by the cross beam 15 to the carriages 12, and through the rack bars 106 and gears 107 to the carriages 13 and thence through the cross bar 17 to the torches 100. The torches are thus actuated by the tracer 50 and reproduces upon the work 41 replicas of the template 36.

In the transmission system shown and described, the rack bars and gears are arranged in the horizontal plane, but they could be arranged in vertical or other planes, if desired. Furthermore, while the articles reproduced by the machine illustrated are of the same dimensions as the pattern or template, the relation of the gears and bars could be set to form any desired proportionately sized reproduction, as for example in the manner described in my copending application above mentioned.

While a single embodiment only of this mechanism has been shown and described, I am not limited thereto since other embodiments can be made without departing from the spirit and scope of the invention as set forth in the following claims.

I claim:

1. A reproducing machine wherein the movement of the reproducing means is controlled by that of a tracer relative to a template, comprising a single tracer, a pair of tracer carriages, means connecting said carriages and supporting said tracer, a plurality of reproducing tools, a pair of carriages supporting said tools and means joining each

tracer carriage to a tool supporting carriage whereby the movement of the tracer relative to a template is transmitted to the tools.

2. A reproducing machine wherein the movement of the reproducing means is controlled by that of a tracer relative to a template, comprising a single tracer, a pair of tracer carriages, means connecting said carriages and supporting said tracer, a plurality of reproducing tools, a pair of carriages, means connecting said carriages and supporting said tools, and means joining each tracer carriage to a tool-supporting carriage whereby the movement of the tracer relative to a template is transmitted to the tools.

3. A reproducing machine wherein the movement of the reproducing means is controlled by that of a tracer relative to a template, comprising a single tracer, a pair of platforms, a pair of tracer carriages, each carriage being reciprocable over a platform, means connecting said carriages and supporting said tracer, a plurality of reproducing tools, a pair of carriages, each carriage being reciprocable over a platform, supporting said tools and means joining the tracer carriage and the tool-supporting carriage on each platform whereby the movement of the tracer relative to the template is transmitted to the tools.

4. A reproducing machine wherein the movement of the reproducing means is controlled by that of a tracer relative to a template, comprising a single tracer, a pair of platforms, a pair of tracer carriages, each carriage being reciprocable over a platform, means connecting said carriages and supporting said tracer, a plurality of reproducing tools, a pair of carriages, each carriage being reciprocable over a platform, means connecting said carriages and supporting said tracer, a plurality of reproducing tools, a pair of carriages, each carriage being reciprocable over a platform, means connecting said carriages and supporting said tools, and means joining the tracer carriage and the tool-supporting carriage on each platform whereby the movement of the tracer relative to the template is transmitted to the tools.

5. A reproducing machine comprising a single tracer and means causing said tracer to move relative to a template, tracer carriages by which said tracer is supported, a plurality of torches, torch carriages by which said torches are supported and means joining each torch carriage to a tracer carriage whereby the movement of the tracer is transmitted through the tracer and torch carriages to said torches.

6. A reproducing machine comprising a platform, a tracer carriage, a torch carriage reciprocable over said platform, and means joining said carriages, a second platform, a tracer carriage, a torch carriage reciprocable over said second platform, and means joining said carriages, means connecting said tracer carriages, a tracer supported by said connecting means, means connecting said torch car-

riages, a torch supported by said second connecting means, a template and a tracer actuator causing said tracer to move relative to said template whereby said torch is caused to move in unison with the tracer.

5 7. In a reproducing machine comprising a platform having a central pedestal, a pair of tracks and carriages reciprocable over said tracks, one carriage being at one side of the pedestal and the other carriage being at the other side, means for transmitting motion from one carriage to the other and causing the carriages to move in opposite directions relative to the pedestal, consisting of a gear mounted to rotate in a horizontal plane over the pedestal and a pair of rack bars which mesh with the teeth of the gear, each bar being supported at one end by a carriage.

20 8. In a reproducing machine comprising a platform having a central pedestal, a pair of tracks and carriages reciprocable over said tracks, one carriage being at one side of the pedestal and the other carriage being at the other side, means for transmitting motion from one carriage to the other and causing the carriages to move in opposite directions relative to the pedestal, consisting of a gear mounted to rotate in a horizontal plane over the pedestal and a pair of rack bars which 25 mesh with the teeth of the gear and vertically spaced tongues on each carriage between which tongues one end of a rack bar is supported.

30 9. In a reproducing machine comprising a platform having a central pedestal, a pair of tracks and carriages reciprocable over said tracks, one carriage being at one side of the pedestal and the other carriage being at the other side, means for transmitting motion from one carriage to the other and causing the carriages to move in opposite directions relative to the pedestal, consisting of a gear mounted to rotate in a horizontal plane over the pedestal, and a pair of rack bars which 35 mesh with the teeth of the gear, vertically spaced tongues on each carriage, between which tongues one end of a rack bar enters, and set screws in said tongues which engage and support the rack bar while permitting 40 a slight oscillation thereof.

45 10. In a reproducing machine the combination with a strip template of a tracer comprising a wheel which bears upon the face of the template strip and roller-grinding means which engage the sides of the strip to insure that the wheel follows the contour of the strip, such roller-grinding means consisting of rollers mounted upon levers pivotally supported upon the tracer and engaging 50 the sides of the strip in advance of the line of contact of the wheel and the strip.

55 Signed by me at Boston, Massachusetts, this eleventh day of March, 1930.

CARLOS KREBS.
